Joy Manufacturing Company, Pittsburgh, Pa.,
a corporation of Pennsylvania

Application October 16, 1948, Serial No. 54,895

11 Claims. (Cl. 262—30)

1

This invention relates to mining machines, and more particularly to a coal mining machine of the flexibly fed, longwall, floor type having embodied therein improved cutting and feeding mechanisms and improved cuttings-removing mechanism.

Coal mining machines for cutting horizontal kerfs in a coal seam in accordance with the longwall method of mining, particularly in mines having very low head room, are usually of the flexibly fed, floor type and slide on their own bottoms directly over the mine floor both during maneuvering and the cutting operation so that the machine height is maintained at a minimum. Such machines have a cutter bar or jib pivotally mounted at the rear end of the machine frame, and such bar or jib is swingable about its pivotal mounting to a substantial angle, close to a right angle, at one side of the machine frame and rigidly locked to the frame so that when the machine is advanced along the coal face a horizontal kerf is cut beneath the coal. The machine is fed over the mine floor by a feed cable wound on a feed drum usually arranged at the front end of the frame, and during the feeding operation the free end of the feed cable is attached to an another jack placed near the coal face in advance of the machine in such a manner that, as the cable is wound in by the drum, the machine is advanced forwardly in an endwise direction along the coal face toward the anchor jack. The feed cable is attachable to the cutter bar hanger to effect swinging of the cutter bar on its pivotal mounting, and the feed cable is employed to swing the bar into a sumped position beneath the coal. A motor is usually arranged centrally of the machine frame intermediate the cutting and feeding mechanisms for driving the cutter chain and the feed drum. The feeding speeds of such feeding mechanism must be variable through a wide range to enable feeding of the cutter bar into the coal in accordance with varying mining conditions. In mining in accordance with the longwall method in low vein mines, the space at the coal face is relatively restricted since the mine roof is propped close to the face with only sufficient room for the machine to move endwise in the space between the face and the roof props, and accordingly, hand shovelling of the cuttings or so-called "gum," created by the cutter bits of the cutter chain during the kerf-cutting operation is an extremely laborious task, and in modern longwall machines a cuttings-removing mechanism or so-called "gummer" is secured to the rear end of the machine at the trailing side

2

of the cutter bar and is usually driven by the machine motor for removing the cuttings or "gum" from the vicinity of the cutter chain and for ejecting the cuttings from the machine. Such cuttings-removing mechanisms are usually in the form of attachments, and accordingly appreciably increase the length of the machine, and, due to their location, hinder setting of cutter bits or picks and must be detached from the machine or partially displaced to permit setting of the bits or picks. Also in known types of cuttings-removing mechanisms for use with reversible mining machines the same must be completely detached from the machine during reversal of the cutter bar position to the opposite side of the machine.

The present invention contemplates improvements over known types of coal mining machines in that improved cutting and feeding mechanisms are provided, constructed in an improved manner, whereby cutting efficiency, a wide range of feeding speeds, as well as extreme compactness and flexibility in operation, are attained. In accordance with the present invention, the cuttings-removing mechanism or "gummer" is built into the machine intermediate the cutting and feeding mechanisms, and is closely associated with the cutting mechanism at the advancing side of the cutter bar whereby the cuttings or "gum" are efficiently removed from the vicinity of the incoming run of the cutter chain and ejected laterally from the prop side of the machine remote from the coal face. By building the cuttings-removing mechanism or "gummer" directly into the machine as a component part thereof, the necessity of bodily removing the mechanism as a unit from the machine or for partially displacing the mechanism is avoided, thereby facilitating the setting of cutter bits or picks, and the cutter bar position may be readily reversed but by the removal of a single small part. The machine is not only simple and compact in design, but is also extremely rugged and reliable in operation, well adapted to meet the demands of service.

45 An object of the present invention is to provide an improved coal mining machine. Another object is to provide an improved mining machine having improved kerf cutting and feeding mechanisms. Yet another object is to provide an improved mining machine of the flexibly fed, floor type especially designed for use in accordance with the longwall method of mining. A still further object is to provide an improved coal mining machine of the pivoted bar, longwall, floor type 50 having an improved pivotal mounting structure

for the cutter bar and improved driving means for the cutter chain. A further object is to provide an improved coal mining machine having an improved cuttings-removing mechanism or "gummer" which is arranged on a longwall mining machine intermediate the cutting and feeding mechanisms and in close association with the cutting mechanism whereby not only are the cuttings efficiently removed from the vicinity of the cutter chain, but also setting of cutter bits or picks and the reversal of the position of the cutter bar are facilitated. Still another object is to provide an improved cuttings-removing mechanism or "gummer" which is constructed as a component part of the machine and which may be readily reversed upon reversal of the machine by but a simple transposition of parts. Another object is to provide an improved cuttings-removing mechanism or "gummer" of the screw conveyor type having improved mounting and driving means for the conveyor screw. Yet another object is to provide an improved screw conveyor for removing the cuttings from the vicinity of the incoming run of the cutter chain of a coal mining machine and arranged in a novel location within the limits of the machine frame. A further object is to provide an improved mining machine feeding mechanism of the variable speed, ratchet and pawl type and embodying improved speed varying means. A still further object is to provide an improved longwall type coal mining machine which is compact and rugged in design and which embodies novel features of construction resulting in increased overall efficiency. These and other objects and advantages of the invention will, however, hereinafter more fully appear.

The aspect of the invention relating to the improvements in the flexible feeding mechanism of the machine is disclosed in divisional application Serial No. 163,301, filed May 20, 1950, while the aspect of the invention relating to the kerf cutting mechanism is disclosed in divisional application Serial No. 252,846, filed October 24, 1951.

In the accompanying drawings there is shown for purposes of illustration one form which the invention may assume in practice.

In these drawings:

Fig. 1 is a plan view of a longwall coal mining machine constructed in accordance with an illustrative embodiment of the invention.

Fig. 2 is a side elevational view of the machine shown in Fig. 1.

Fig. 3 is a view in central longitudinal vertical section taken substantially on the plane of line 3—3 of Fig. 1, with the cutter bar in longitudinal alignment with the machine frame.

Figs. 4 and 5 are detail views showing the high and low speed feed control levers in different positions, and with parts in section to show the interlock between the control levers.

Fig. 6 is an enlarged horizontal sectional view taken substantially on the plane of line 6—6 of Fig. 3, showing details of the cutting mechanism and the associated cuttings-removing mechanism or "gummer."

Fig. 7 is an enlarged cross sectional view taken substantially on the plane of line 7—7 of Fig. 2 illustrating details of the cuttings-removing mechanism or "gummer."

Fig. 8 is a detail view illustrating a portion of the driving gear for the cutting and cuttings-removing mechanisms.

Fig. 9 is a detail vertical section taken on the plane of line 9—9 of Fig. 8.

Fig. 10 is a side view of the combined guard and conveyor housing member.

Fig. 11 is a vertical sectional taken on the plane of line 11—11 of Fig. 10.

Fig. 12 is a top view of the guard and housing member shown in Fig. 10.

Fig. 13 is a detail vertical sectional view taken on the plane of line 13—13 of Fig. 6, but on a reduced scale, showing details of the conveyor housing and conveyor screw.

Fig. 14 is an enlarged horizontal sectional view taken substantially on the plane of line 14—14 of Fig. 2.

Fig. 15 is a longitudinal vertical sectional view taken substantially on the planes of line 15—15 of Fig. 14.

Fig. 16 is a horizontal sectional view taken substantially on the planes of line 16—16 of Fig. 15.

Fig. 17 is a longitudinal vertical sectional view taken substantially on the planes of line 17—17 of Fig. 14.

Fig. 18 is a detail horizontal sectional view taken substantially on the plane of line 18—18 of Fig. 17.

In this illustrative embodiment of the invention, as shown in the drawings, the coal mining machine is generally designated 1 and generally comprises a compact low height machine frame 2 slidable on its bottom 3 for movement over the floor of a mine and carrying at its rear end a kerf cutting mechanism 4, at its front end a flexible feeding mechanism 5, and having a cuttings-removing mechanism or so-called "gummer" 6 associated with the cutting mechanism; said cutting and feeding mechanisms and said cuttings-removing mechanism being driven by a motor 7 arranged longitudinally centrally of the machine frame intermediate the cutting and feeding mechanisms. The cuttings-removing mechanism or "gummer" is built into the machine within the limits of the machine frame and is closely associated with the cutting mechanism, and is so arranged at the advancing side of the cutter bar as to receive the cuttings from the vicinity of the incoming run of the cutter chain and to convey the cuttings laterally away from the coal face and to eject positively the cuttings laterally from the machine at the side thereof close to the line of the roof props. While the invention is shown embodied in a longwall floor type coal mining machine, it will be evident that various features thereof may be embodied in coal mining machines of other types.

The machine frame 2, in this instance, comprises a rear cutter frame section 10, a front feed frame section 11 and a central motor frame section 12, and these frame sections are suitably rigidly united to provide a low compact frame unit structure slidable over the mine floor. Pivotally mounted on the cutter frame section 10 is a horizontal plane cutter bar or jib 13 having a cutter bit or pick carrying cutter chain 14 guided for circulation about its margin. Carried by the feed frame section 11 is a large horizontal feed drum 15 on which a feed cable 16 is wound. Arranged near the four corners of the feed frame section 11 at the sides of the drum are horizontal guide rollers 15^a, 15^b, 15^c, 15^d, and the feed cable may be extended from the drum about these guide rollers during the various operations of the machine. The cuttings-removing mechanism or "gummer" 6 is embodied in the cutter frame section 10 rearwardly of the motor frame section 12, at the advancing side of the cutter bar. The mo-

tor frame section 12 houses the motor 7, which is herein preferably an electric motor, having its armature shaft 17 horizontally disposed and extending longitudinal of the machine frame at one side of the longitudinal center of the frame, as shown in Fig. 1.

Now referring to the detail structure of the kerf cutting mechanism 4, it will be noted that fixed to the rear end of the motor shaft 17 is a spur motor pinion 20 (Figs. 6, 8 and 9) adapted to mesh with and drive a spur gear 21. This spur gear is splined at 22 (Fig. 3) to a horizontal longitudinally extending shaft 23 suitably journaled within the cutter frame section. This spur gear has its hub annularly grooved at 24 with which a shipper yoke 25 (Figs. 8 and 9) engages, and this yoke is secured to a longitudinal control rod 26 having a handle 27 conveniently located at the front end of the machine (Figs. 1 and 14). Thus the spur gear 21 may be slid at will into and out of mesh with the motor pinion. The shaft 23 has keyed thereto a bevel pinion 28 which meshes with and drives a large horizontal bevel gear 29 (Fig. 3) which has its hub keyed to a vertical tubular shaft 30. The shaft 30 is journaled at its upper end on a roller bearing 31 supported by a detachable top cover plate 32, and is journaled near its longitudinal center on a roller bearing 33 supported by a circular bearing support or bearing annulus 34, coaxial with the shaft 30 and on which the cutter bar or jib is pivotally mounted, as hereinafter explained. A cap 35, detachably secured to the cover plate, has an integral shaft 36 which extends centrally through the tubular shaft 30 and is threadedly attached at 37 within a threaded boss integral with a detachable bottom plate 38. The shaft 36 rigidly ties the superimposed top and bottom plates of the cutter frame section together. Keyed to the lower portion of the shaft 30 is the hub of a chain sprocket 39 which engages and drives the endless cutter chain 14. The lower end of the shaft 30 is annularly grooved at 40 and a split ring 41 secured as by screws to the sprocket hub has a flange 42 fitting in this groove to hold the sprocket against displacement axially of the shaft. The upper end of the shaft 30 is grooved to receive a split ring 43 which engages the upper surface of the inner race of the upper roller bearing 31. The lower end of the hub of the bevel gear 29 and the upper end of the sprocket-hub abut the opposed end surfaces of the inner race of the lower roller bearing 33. A dirt seal 44 carried in a recess in the upper portion of the tubular shaft 30 sealingly engages the inner shaft 36 to prevent access of dirt to the upper roller bearing. The bearing support 34 carries a similar dirt seal 45 which sealingly engages the sprocket hub to prevent access of dirt to the lower roller bearing and to prevent leakage of lubricant from the frame chamber 46 in which the bevel gears are arranged.

In this improved construction, the bearing support or annulus 34 supports bearing sleeves 48 (Fig. 3) on which a hub 49 of a hanger frame 50 is swivelled, and the cutter bar 13 is secured to and supported by this hanger frame to swing horizontally relative to the machine frame. An annular retaining plate 51 is secured as by screws to the bottom of the bearing annulus 34 for retaining the hub of the hanger frame in position on its bearings. The hanger frame has an upstanding boss 52 grooved at 53 to receive an arcuate guiding flange 54 on the cutter frame. A

rotary locking pin 55 is arranged in a bore in the boss 52 and is grooved at 56 to receive the guide flange 54 and has a circular body portion which, upon rotation of the pin, is receivable in any one of three spaced notches 57 in the guide flange 54 for rigidly locking the cutter bar in its different positions to the machine frame. The feed cable 16 is attachable to this locking pin for effecting swinging of the cutter bar 13 on its swivel mounting, as hereinafter explained. From the foregoing, it will be evident that when the gear 21 is in mesh with the motor pinion 20 and the motor is running, the cutter chain 14 may be rapidly circulated about the margin of the cutter bar 13 through the motor pinion, the spur gear 21, the shaft 23, the bevel pinion 28, the bevel gear 29, the vertical shaft 30 and the chain drive sprocket 39, and when the gear 21 is slid out of mesh with the motor pinion the cutter chain may remain idle during running of the machine motor. The pivotal mounting structure for the kerf cutting mechanism is being claimed in my copending divisional application Serial No. 252,846 mentioned above.

The feeding mechanism 5 is being claimed in my copending divisional application Serial No. 163,391 above referred to and comprises a spur pinion 60 (Fig. 14) keyed to the front end of the motor shaft 17 and meshing with and driving a spur gear 61 secured to a horizontal, longitudinally extending shaft 62 suitably journaled in the feed frame section 11. Secured to and driven by the shaft 62 is a worm 63 (Figs. 16 and 17) meshing with and driving a worm wheel 64 (Fig. 15), the latter in turn having its hub 65 secured to a vertical shaft 66, herein journaled on an upper ball bearing 67 supported by a bearing boss 67' integral with a top cover plate 68 and on a lower ball bearing 69 supported within a bearing boss 69' integral with a horizontal web 70 of the feed frame section. The gear hub 65 has an eccentric portion or crank 71, to be later referred to. Formed on the upper portion of the gear hub 65 is a spur gear 72 meshing with and driving a spur gear 73 having its hub journaled on a bearing 74 supported by a vertical shaft portion 75 of a swinging gear support 76. The support 76 comprises upper and lower support sections 77 and 78 secured together as by a screw 79 arranged within the shaft portion 75, and these support sections have hubs 80 swivelly mounted on the bearing bosses 67' and 69' (Fig. 15) to swing in horizontal planes. The gear 72 is adapted to mesh with and drive a spur gear 81 (Fig. 17) having its tubular hub journaled in upper and lower ball bearings 82 and 83 respectively supported by the cover plate 68 and the horizontal web 70. The gear hub is keyed to a vertical shaft 84 which has secured thereto and drives a spur gear 85 meshing with a large internal gear 86 on the cable winding drum 15 of the feeding mechanism. The feed drum has a hub 87 journaled on vertically spaced ball bearings 88 supported by a vertical shaft 89 provided with a top flange 90 secured as by screws to the frame-web 70. A detachable bottom plate 91 is secured to the feed frame section and has an upstanding boss 92 secured as by a screw to the shaft 89. The drum is arranged horizontally between the horizontal web 70 and the bottom plate 91, as shown in Fig. 15. It will be seen from the foregoing description that when the gear 73 is swung into mesh with the gear 81 the feed drum may be driven in cable winding direction at a relatively high speed suitable for

machine-maneuvering through the motor pinion 60, spur gear 61, shaft 62, worm gearing 63, 64, shaft 66, spur gears 72 and 73, spur gear 81, shaft 84 and spur gear 85 meshing with the drum-gear 86. The swingable support 76 may be swung on its pivotal mounting by an eccentric portion or crank 93 (Figs. 14, 15 and 16) received in a vertical slot 84 (Fig. 15) in the lower support section 78, and this crank is integral with an operating shaft 95 which is horizontally and longitudinally disposed and suitably journaled within bearing sleeves 96 supported within the feed frame section. Secured to this shaft is the hub 97 of an operating lever 98 likewise conveniently located at the front end of the machine. Thus the swingable support 76 may be swung to move the high speed gear 73 into and out of mesh with the gear 81. The operating lever 98 has a conventional detent lock for holding the same in its different positions of adjustment.

Now referring to the variable low speed drive for effecting rotation of the feed drum 15 in cable winding direction through a wide range of low feeding speeds suitable for cutting, it will be noted that pivotally connected to the crank 71 is one end of a connecting rod or link 100 (Figs. 15 and 16) which is pivotally connected at its opposite end to an oscillatory pawl carrier 101 of a step by step ratchet and pawl device. This pawl carrier comprises upper and lower plates 102 and 103 provided with hubs 104 pivotally mounted on bearing sleeves 105 supported by the hub 106 of a toothed ratchet wheel 107 (Fig. 16). The hub of this ratchet wheel is keyed at 108 to the hub of the gear 81 (Fig. 17). The carrier-plates 102, 103 are secured together by studs 109, 110, and the stud 108 supports bearing sleeves for the connecting rod 100. The other stud 110 supports bearing sleeves for a pivoted driver pawl 111 which is yieldingly urged toward engagement with the ratchet teeth by a coiled tension spring 112. A second pawl 113 (Fig. 16) suitably pivoted at 114 on the feed frame is yieldingly held in engagement with the ratchet teeth by a coiled tension spring 115. The pawl 113 is reversely positioned with respect to the pawl 111 and serves to hold the ratchet wheel against reverse rotation during movement of the driver pawl into its different tooth engaging positions. A shield member 116 (Fig. 18) is rotatably mounted on a bearing sleeve 117 (Fig. 17) supported by the hub of the ratchet wheel, and this shield is rotatable about an axis alined with the axis of rotation of the ratchet wheel, and is adapted variably to shroud the ratchet teeth to vary the engagement of the driver pawl 111 with the ratchet teeth to obtain variable speed drive, as later explained. This shrouding-shield 116 is formed with a bevel gear segment 118 with which a bevel gear 119 formed on a horizontal longitudinally extending shaft 120 (Fig. 17), meshes. The shaft 120 is journaled within the feed frame section and has keyed thereto the hub 121 of an operating lever 122 likewise conveniently located at the front end of the machine. The lever 122 has a conventional detent lock for holding the same in its different positions. Thus the shield may be turned by the lever to vary the action of the driver pawl on the ratchet wheel to provide a wide range of intermittent variable speeds. The shield 116 has circumferentially spaced, smooth arcuate surfaces 123 and 124 (Fig. 18) so that when the lever 122 is in its position to release the ratchet-drive these surfaces respec-

tively serve to hold the pawls 111 and 113 out of contact with the ratchet teeth, with the pawls riding back and forth along the surfaces 123 and 124 as the pawl carrier oscillates.

An interlock is provided between the high and low speed control levers 98 and 122 so that when the high speed drive is effective the low speed drive is maintained in its inoperative position, and vice versa. This interlock comprises a sliding locking bar or locking plunger 125 guided at 126 on the feed frame section and having tapered portions 127 at its opposite ends selectively receivable in appropriately located detent-notches 128 and 129 in the lever hubs. This shiftable locking bar is of such a length that it must be received in one notch before it can be released from the other notch. In Fig. 4, the fast speed lever 98 is locked against movement by the locking bar 125 while the low speed lever 122 is free to be turned. In Fig. 5, the locking bar 125 is in its opposite position with the low speed lever 122 located in off position and with the high speed lever 98 free to be turned. Thus the concurrent connection of the high and low speed drives with the feed drum is prohibited.

The cuttings-removing mechanism or so-called "gummer" 6 will now be described in detail. As shown in Fig. 3, the shaft 23 of the cutter chain drive has a worm 135 formed thereon which meshes with a worm wheel 136 (see also Figs. 6 and 7) having its hub keyed to alined horizontal shafts 137. These shafts extend across the cutter frame section 10 rearwardly of the motor and are journaled on laterally spaced ball bearings 138, 139 arranged at opposite ends of the worm wheel hub, as shown in Figs. 6 and 7, and supported within a bearing bracket 139 integral with the cutter frame section. Arranged within this bearing bracket at the outer sides of the bearings are dirt seals 140 which sealingly engage the shafts 137 to prevent access of dirt to the ball bearings. The cutter frame section has side recesses or chambers 141 and 142, and the tubular shafts 137 extend in opposite directions from the bearings 138 substantially to the inner walls 143 of these recesses, as shown. Arranged in the recess 141 at the outer side of the machine remote from the side from which the cutter bar projects, i. e. the side of the machine remote from the coal face and nearer to the prop line, is a conveyor screw or spiral conveyor 144 secured to one end of a shaft 145 which is telescopically arranged in and splined at 145' to the tubular shafts 137. The hub of the conveyor screw 144 is secured to the shaft 145 by a bolt 146 which is adapted to shear upon overload and prevent damage to the parts. The shaft 145 supports a bearing sleeve 147 on which the conveyor hub is journaled so that the conveyor may freely revolve relative to the shaft upon shearing of the bolt. A screw and washer 148, 149 attached to the opposite end of the shaft 145 serve to secure the shafts 137 and 145 axially together, and the screw 148 is readily accessible through the opposite empty recess 142 so that the conveyor screw may be readily detached from the shaft 137, and reversed end for end and reattached to the opposite end of the shaft 137 with the conveyor screw at that time received in the opposite recess 142, thereby to enable the "gummer" to operate in the reverse direction with the cutter bar swung to the opposite side of the machine frame, as later explained more in detail. Attached to the cutter frame section 10 at the face side of the machine

is a combined guard and conveyor housing member 150 which has a narrow forward longitudinal vertical deflector wall portion 151 and a relatively wide partially-circular housing portion 152. The wall of each recess 141, 142 is partially circular at 153 and the wall 154 of the housing portion 152 cooperates with the recess wall to provide a substantially circular enclosure for the spiral vanes of the conveyor screw. The combined guard and housing member 150 is transposable, and, like the conveyor screw, may be placed at either side of the cutter frame section, depending upon the direction in which the machine is operating to cut, and has a bottom positioning pin 155 which is receivable in either one of a pair of longitudinal notches or slots 156 in the bottom plate 38 of the cutter frame section. The guard and housing member 150 also has an upper guide rib 157 which is receivable in either one of a pair of longitudinal guide slots 158 cut in the bottom of the arcuate guide flange 54 at the opposite sides of the cutter frame section, and stop pins 159 secured to the cutter frame section (Fig. 13) near the inner ends of the guide slots serve to limit inward movement of the guide rib 157 in either slot, properly to position the partially circular housing portion 152 with respect to the cooperating recess wall. An eye-bolt 160 is pivotally connected at 161 to the guide and housing member 150 and is selectively receivable in notches 162 formed in the opposite sides of the arcuate guide flange 54 and a wing nut 163 threaded on the bolt, when tightened, clamps the guard and housing member firmly in position. Thus the conveyor screw 144 and the guard and housing member 150 may be detached and transposed into positions at either side of the cutter frame section. The conveyor screw 144, when the gear 21 is slid into mesh with the motor pinion 20, may be driven from the machine motor and operates in unison with the cutter chain, and the conveyor screw may be disconnected from its drive whenever the gear 21 is slid out of mesh with the motor pinion. The conveyor screw is so arranged at the advancing side of the cutter bar or jib, as shown in Fig. 6, that the incoming run of the cutter chain moves the cuttings back from the kerf inwardly through the chamber 142 beneath the bearing bracket 139 (Fig. 7) for the conveyor drive shaft, toward the conveyor screw, and the conveyor screw receives the cuttings and forces them outwardly through the chamber 141 at the outer side of the machine. The vertical deflector portion 151 of the guard member serves to direct any cuttings which might be carried past the conveyor screw by the cutter chain (as the latter moves around the drive sprocket 39) in a rearward direction into the machine path at the trailing side of the cutter bar, and also serves to prevent the pile of cuttings which have been discharged laterally from the conveyor screw from crowding back toward the path of the cutter chain. Due to the location of the screw conveyor 144 at the advancing side of the cutter bar, as shown in Fig. 6, the rear end of the cutter frame section is maintained open so that free access to the cutter bits or picks for setting purposes is at all times provided. Simply by removing the guard and housing member 150 from the machine frame the cutter bar may be swung horizontally to either side of the machine frame, and the guard and housing member may be quickly and readily released from the machine

frame simply by loosening the wing nut 163 and throwing out the eye-bolt 160 from its cooperating notch 162 and sliding the same in a rearward direction from the cutter frame section. In like manner, the guard and housing member may be quickly reattached to the cutter frame section at the opposite side of the machine frame. The general mode of operation of the improved coal mining machine is as follows. The machine may be fed over the mine floor during maneuvering by the feed cable 16 which is extended from the feed drum and attached at its free end to an anchor jack and wound in at a high speed by the feed drum 15 through the high speed gearing, and during such maneuvering the cutter bar 13 is usually locked by the pin 55 in longitudinal alignment with the machine frame as shown in dotted lines in Fig. 1. When the mining machine is properly positioned with respect to the coal face, the fast speed drive for the feed drum is disconnected and the feed cable is detached from the anchor jack and extended rearwardly from the drum around the guide roller 15^a, along the face side of the machine and attached at its free end to the locking pin 55 on the bar hanger frame. The handle 27 is then positioned to place the gear 21 in mesh with the motor pinion 20 to connect the cutter chain 14 to the machine motor. The locking pin 55 is then turned into its unlocked position, and as the feed drum 15 is rotated at a slow speed to wind in the feed cable the cutter bar is swung horizontally about its pivot into its sumped position within the coal, as shown in full lines in Fig. 1. The locking pin is then turned into its locking position to lock the cutter bar rigidly to the machine frame, and the feed cable is detached from the locking pin and is extended forwardly from the machine around the guide roller 15^b to an anchor jack located at the coal face in advance of the machine. The lever 122 is then positioned to connect the intermittent slow speed drive, with the ratchet set to obtain the desired feeding speed, and the feed drum is rotated to wind in the feed cable to advance the machine in an endwise direction forwardly along the coal face thereby to cut a horizontal kerf beneath the coal. By varying the position of the shrouding-shield 116 the engagement of the driver pawl 111 with the ratchet teeth may be varied thereby to vary the intermittent low speed drive of the feed drum between the maximum and minimum limits, as desired. As the mining machine is advanced at a low cutting speed along the coal face, the cuttings created by the cutter bits or picks of the cutter chain and carried back from the kerf by the incoming run of the cutter chain, are received by the conveyor screw 144 and ejected laterally from the outer side of the machine toward the line of the roof props. When it is desired to cut in the opposite direction, the conveyor screw 144 and the combined guard and housing member 150 may be detached from the machine, the feed cable is wound in the opposite direction on the feed drum, the cutter bits are reversed on the cutter chain and the machine motor is reversed, and then the feed cable is attached to the locking pin on the bar hanger frame to swing the cutter bar into a substantially right angle position at the opposite side of the machine frame, and the bar is thereafter locked in position by the pin. The conveyor screw and the combined guard and housing member are then reattached to the opposite side of the cutter

11

frame section 10 with the conveyor screw reversed end for end and positioned in the opposite recess 142. Since the general mode of operation of a longwall coal mining machine is well known to those skilled in the art, further discussion of the mode of use of the machine is herein unnecessary.

As a result of this invention an improved coal mining machine is provided which is extremely flexible and efficient in operation and which may be readily reversed to cut in either of opposite directions by a simple repositioning of parts. The kerf cutting mechanism is simple and rugged in design, enabling efficient cutting of coal. By the building of the cuttings-removing mechanism or so-called "gummer" directly in the machine at the advancing side of the cutter bar the cuttings are effectually removed from the vicinity of the incoming run of the cutter chain as rapidly as they are carried back from the kerf and are positively ejected from the side of the machine out of the machine path. The novel location of the cuttings-removing mechanism or "gummer" within the limits of the machine frame maintains the overall dimensions of the machine at a minimum. The cuttings-removing mechanism or "gummer" may operate in a reverse direction during reverse cutting by a simple transposition of parts, and the removal of but a single part enables swinging of the cutter bar into its reversed positions at either side of the machine frame. Moreover, due to the novel location of the cuttings-removing mechanism or "gummer" free access to the cutter bits or picks for setting purposes is at all times provided. Other advantages of the invention will be clearly apparent to those skilled in the art.

While there is in this application specifically described one form which the invention may assume in practice, it will be understood that this form of the same is shown for purposes of illustration, and that the invention may be modified and embodied in various other forms without departing from its spirit or the scope of the appended claims.

What I claim as new and desire to secure by Letters Patent is:

1. A reversible cuttings-removing mechanism adapted for use with a reversible coal cutting machine of the longwall type comprising a frame movable endwise along a longwall face and on the rearward portion of which a cutter bar is pivotally mounted for horizontal swinging movement into positions at either side of said frame depending upon the direction of operation of the machine, and about which bar an endless cutter chain is guided for orbital circulation, said frame having a chamber for receiving the cuttings brought back from the kerf by the incoming run of the cutter chain and having coaxial bores one at each side of said frame between the advancing end of the latter and the bar pivot with said bores extending transversely of said frame at the leading side of said cutter chain in either bar position and communicating with said chamber, said cutter bar being swingable horizontally about its pivot into its reversed positions with respect to said frame at the opposite sides of the latter as aforesaid and the incoming run of the cutter chain in either reversed position of said bar moving through the then-vacant bore at the inner face side of the frame, a transposable conveyor screw disposable in said bore at the outer side of said frame remote from the coal face for receiving

12

the cuttings within said frame-chamber and for moving the cuttings laterally in said outer bore and for positively ejecting the cuttings from said bore at the outer side of said frame, and driving mechanism on said frame for rotating said conveyor screw in either of its transposed positions in said bores.

2. A cuttings-removing mechanism as set forth in claim 1 wherein said driving mechanism for said conveyor screw comprises transverse shafting journaled within said frame, said screw having a drive shaft secured thereto, and a releasable connection is provided between said transverse shafting and said screw shaft whereby said screw may be driven by said shafting in either of its transposed positions.

3. A cuttings-removing mechanism as set forth in claim 2 wherein said transverse shafting is hollow and said screw is axially receivable in said hollow shafting, and said releasable connection comprises splineways on said screw-shaft coaxing with splines within said hollow shafting whereby said screw shaft may be removed axially from its splined connection with said shafting without disturbing the relation of said shafting with respect to its journal within said frame.

4. A cuttings-removing mechanism as set forth in claim 2 wherein said releasable connection is located with the then-vacant bore at the face side of the machine and serves to secure said screw shaft and said hollow shafting against relative axial displacement, and said releasable connections being accessible from the exterior of the machine through said inner bore.

5. A cuttings-removing mechanism as set forth in claim 1 wherein said transverse bores have partially circular walls, and a transposable guard is attachable to said frame at the outer side thereof during either direction of operation of the machine for directing the cuttings toward the conveyor screw in either of the reversed positions of the latter, and having a curved housing portion cooperating with the bore-walls to provide a complete circular bore in which the conveyor screw is receivable with the bore-walls completely surrounding the screw and having an open inner end for receiving the cuttings conveyed inwardly into said chamber by the incoming run of the cutter chain.

6. A cuttings-removing mechanism as set forth in claim 5 wherein said guard extends longitudinally along the open outer side of said frame outwardly of the cutter chain further to provide the cuttings discharged laterally from the outer side of said frame by said conveyor screw from crowding back toward the cutter chain in either transposed position of said guard.

7. A cuttings-removing mechanism adapted for use with a coal cutting machine and comprising a frame having a chamber in which the inner portion of the cutter chain is arranged whereby the cuttings are brought back from the kerf by the incoming run of the cutter chain into said chamber, said frame having a transverse bore at one side thereof, said bore having a partially circular wall, a removable guard and housing member attached to said frame at said side and having a curved housing portion cooperating with the bore-walls to provide a substantially circular-wall bore, and a conveyor screw journaled on said frame and arranged in said bore with the circular walls of the latter surrounding said screw whereby the latter may receive cuttings in said chamber and move

13

them outwardly through said bore to discharge laterally from the outer side of said frame.

8. A cuttings-removing mechanism as set forth in claim 7 wherein said guard extends longitudinally along said side of said frame outwardly of the cutter chain for preventing the cuttings discharged laterally from said frame by said conveyor screw from crowding back toward the cutter chain in said chamber.

9. In combination, a frame movable endwise along a longwall face, a cutter bar mounted on the rearward end portion of and projecting laterally from said frame, said bar having an endless cutter chain guided for circulation about its margin, said frame having a chamber in which the inner portion of said cutter chain is arranged whereby the incoming run of said chain brings the cuttings back from the kerf into said chamber, motor operated driving connections for said cutter chain including a horizontal shaft extending longitudinally of said frame, said frame having a transverse bore located in a transverse zone between the front advancing end of said frame and the forward side of said chamber at the leading side of said cutter chain and communicating with said chamber, a conveyor screw arranged in said bore and journaled on said frame for moving the cuttings in said chamber outwardly through said bore and for ejecting the cuttings laterally from the outer side of said frame, and a driving connection between said longitudinally extending horizontal shaft and said conveyor screw.

10. A cuttings-removing mechanism as set forth in claim 9 wherein said driving connection between said longitudinal shaft and said conveyor screw includes a worm on said shaft, a worm wheel meshing with and driven by said worm, and transverse shafting journaled within said frame in coaxial relation with said bore and driven by said worm wheel, and a connection is provided between said transverse shafting and said conveyor screw whereby said shafting effects screw rotation.

11. A reversible cuttings-removing mechanism adapted for use with a reversible coal cutting machine of the longwall type comprising

14

a frame movable endwise along a longwall face and on which a cutter bar is mounted with said bar projecting laterally from the rearward end portion of said frame and carrying a reversible endless cutter chain, said frame having a chamber within which the inner portion of the cutter chain is arranged whereby the cuttings brought back from the kerf by the incoming run of the cutter chain are discharged into said chamber irrespective of the direction of operation of the machine, said frame having transverse bores one at each side of said frame with said bores located between the advancing end of said frame and the forward side of said chamber, said bores communicating with the forward side of said chamber, and a transposable conveyor screw positionable selectively within said bores at the opposite sides of said frame depending upon the direction of operation of the machine and in either transposed operating position located at the advancing side of said cutter bar in adjacency to the incoming run of the cutter chain, said conveyor screw in either transposed operating position moving the cuttings from said chamber through its bore to discharge at the outer side of said frame.
